UNITED STATES PATENT OFFICE.

NELLE M. PETERS, OF CHICAGO, ILLINOIS.

KIMONO.

1,104,445.

Specification of Letters Patent. Patented July 21, 1914.

Application filed August 4, 1913. Serial No. 782,847.

To all whom it may concern:

Be it known that I, NELLE M. PETERS, a citizen of the United States, residing at Chicago, in the county of Cook and State of Illinois, have invented certain new and useful Improvements in Kimonos, of which the following is a specification.

The essential object of this invention is to provide a kimono or similar garment which is made of one piece but which, when worn, cannot be distinguished from a garment of ordinary construction.

In the drawings, Figure 1 is a front view of the garment as the same appears when in use; Fig. 2 is a rear view; and Fig. 3 is a view of the garment before same is placed upon the person.

As previously stated, the garment is made in one piece and is shown in the drawings as provided with suitable fringe or edging at sundry places. The head of the wearer is inserted through the perforation 1 and then the opening 2 is closed by the eyes 3 and hooks 4. The hooks 5 are secured upon the garment to what is the under surface in Fig. 3, and each of said hooks is adapted to engage an eye 6 and an eye 7. The hook is beneath the ornamental bow 8 and on the opposite side of the garment to said bow. When the hooks 5 engage the eyes 6 and 7, the garment will be caught up and held in the position shown in Fig. 1, and the garment will be suspended from the shoulders of the wearer, draping over the arms so as to protect the same. The garment will have the appearance of being provided with sleeves although it is in fact sleeveless. The right-hand end 9, Fig. 3, will become the front, Fig. 1, and the left-hand end 10, Fig. 3 will become the back. That part of the garment designated 11 will form the sleeve.

Still further hooks and eyes may be applied in order to keep the front and back from separating, and other fastening devices may be substituted for hooks and eyes.

The hooks 5 should be fixed a little nearer to the end 10 than they are to the perforation 1. The eyes 6 are nearer to the end 9 than they are to the perforation 1, whereas the eyes 7 are approximately midway between the perforation 1 and the end 9. To the right of the eyes 7 the fringe or edging may be omitted and the garment provided with a dart or indent 12 between

the eyes 6 and 7, this construction being desirable in order to prevent too great a gathering of material when the hooks 5 are in engagement with the eyes 6 and 7.

Although it is best to make the garment absolutely without seams and to form the same out of a single piece of material, that construction is not absolutely necessary and it is entirely feasible to make the garment out of two or more separate pieces of fabric sewed or otherwise secured together. The only requisite is that the garment, whether made of a single piece of material or of two or more pieces secured together, shall, when spread out flat, be shaped substantially as indicated in Fig. 3.

It will be obvious that sundry changes in the details of cut and the like may be made without departing from the scope of the invention.

I claim as my invention:

1. A one-piece garment provided with a perforation or aperture adapted to receive the head of the wearer, a hook upon one surface of the garment, and a pair of eyes upon the other surface of the garment, both of said eyes being adapted to be engaged by said hook.

2. A garment formed of a single piece of material and having a perforation adapted to receive the head of the wearer, an opening extending from said perforation, means to close said opening, a fastening device on one surface of the fabric and a pair of fastening devices on the opposite surface, both adapted to be engaged by said first-mentioned fastening device.

3. A garment formed of a single piece of material and having a perforation adapted to receive the head of the wearer, an opening extending from said perforation, means to close said opening, a fastening device on one surface of the fabric, and means upon the other surface of the fabric adapted to coöperate with said fastening device, there being a fullness or gathering of the material on said second-mentioned side of the fabric adjacent the point where same is secured to said fastening device.

In testimony whereof I hereunto affix my signature in the presence of two witnesses.

NELLE M. PETERS.

Witnesses:

EDWARD M. PETERS,
ROBT. KLOTZ.
